(57) **CLAIM**

I claim the ornamental design for a divan, as shown and described.

DESCRIPTION

FIG. 1 is a perspective view of a divan;

FIG. 2 is a right side view of a divan;

FIG. 3 is a left side view of a divan;

FIG. 4 is a top view of a divan;

FIG. 5 is a bottom view of a divan;

FIG. 6 is a front view of a divan; and,

FIG. 7 is a back view of a divan.

Any broken line illustration in the drawings are not part of the design sought to be patented.
